FIXATION CHART

Filed Feb. 27, 1928

Fig. 5.

Inventor
Jacob Copeland,
Orlo M. Vernich
Atty.

UNITED STATES PATENT OFFICE

JACOB COPELAND, OF CHICAGO, ILLINOIS

FIXATION CHART

Application filed February 27, 1928. Serial No. 257,167.

The invention relates to fixation charts for use by refractionists in examining the eyes of a patient by causing the patient to fix his attention upon said charts, and particularly to 5 a means whereby said charts may be interchangeably associated with a holder for the charts, the latter having means whereby said holder may be separably connected with a rod of a photoptometer, or be detachably connected for use to the person of the refractionist.

In addition to the above, it is a further object to produce a construction having the above advantages, and to provide said construction with means, whereby said holder may be moved or shifted relatively to the support with which it may be attached, and thereby allow the holder, in the event of its being attached to the head of the refractionist, to be shifted from one eye to another, or to an intermediate position between the eyes, to thereby arrange the holder in a manner to allow the use of a retinoscope, or other instrument, to facilitate the examination of a patient's eye, or to allow free use of both eyes of the refractionist, and to also cause the patient to position his eye, so that the refractionist may make his examination of conditions with the eye of the patient in 30 various positions.

It is another object of the invention to provide the device with means whereby the axes of said chart holder are maintained in horizontal and vertical alignment, regardless of 25 the positions which said charts and chart holder may assume upon movement thereof to and from the positions thereof above referred to.

It is also an object to provide a construction, in which the chart holder may be rotated with respect to the element in which it is mounted, and thereby provide a means whereby certain other tests may be accomplished, such as for instance, a near point astigmatism test, wherein rotation of the chart is of advantage.

In addition to the above, it is also an object to employ an element which provides a mounting, whereby the device may be removably mounted with respect to a support, such

as a head gear secured to the head of the refractionist, or be removably mounted relatively to a bar of a photoptometer the mounting having means, whereby electrical connection may be formed between a source of current and the illuminating element for the charts. 55

The invention has these and other objects, all of which will be explained in detail, and more readily understood when read in conjunction with the accompanying drawings, which illustrate one construction, whereby the above and other advantages may be accomplished, it being obvious, however, that changes and modifications may be resorted to without departing from the spirit of the appended claims forming a part hereof. 60

In the drawings:

Fig. 1 is a front view of the device, associated with a head band, showing in dotted lines the changed positions which the device may assume;

Fig. 2 is a side view of the device shown in Fig. 1;

Fig. 3 is a side view showing the device applied to a Maddox bar;

Fig. 4 is a sectional view taken on line 4—4 of Fig. 1; and

Fig. 5 is a view of one of the several charts which may be employed in the device. 65

One embodiment of the invention contemplates the provision of a structure which may be removably associated with a head band 10, having a bracket, generally designated 11, secured thereto, the bracket being provided to allow the fixation chart holder, generally designated 12, to be detachably connected therewith. The chart holder is designed to allow it to be shifted from a position between the eyes of the refractionist to either one side or the other in front of either eye; thus allowing the holder to be arranged to permit free use of both eyes of the refractionist, or to be located in front of either eye and permit the use of a retinoscope or other instrument applied to the other eye during the examination of the eyes of the patient. 70

The invention contemplates the provision of means whereby various charts may be

interchangeably mounted with respect to the chart holder and the illumination of the chart, and to provide a construction, whereby the holder may be shifted from one eye to the other of the refractionist, which construction will maintain the horizontal and vertical axes in their vertical and horizontal relation, regardless of the position which the chart holder is caused to assume upon movement thereof relatively to the eyes of the refractionist.

The chart holder is movably mounted with respect to its mounting or head band, for the further reason to allow said holder to be arranged in a manner to position the eye of the patient, so that examination thereof may be accomplished with the eye of the patient in different positions.

Provision is also made for rotating the chart holder, so that certain other tests, such as a near point astigmatism test may be accomplished, should this be found necessary or desirable.

The device, as illustrated, contemplates the use of a member 13, which is designed to be detachably mounted with respect to the bracket 11, of a head gear band 10, or upon a photoptometer rod, and to provide a support for the reflector 14, which is mounted for movement in lateral directions in the manner and for the purpose above described. This reflector 14 is secured to the member 13, through the medium of the arms 15 and 16, which are, respectively, pivotally connected at one end with the member 13 at 17 and 18, and have their opposite ends connected with the reflector support and lamp socket, generally designated 19. The connections between the arms and the member 13 provide a means, whereby the arms and the elements connected therewith are frictionally held in any of their various positions of adjustment, and to this end a split washer 20 is located between the arms and a portion forming part of the connections 17 and 18, by which the arms are connected with the member 13, which will frictionally hold said arms and certain parts connected therewith in their various positions of adjustment.

The lamp socket and reflector support 19 is composed of a plate 21, and a correspondingly shaped insulating member 22, the plate 21 being provided with the tubular portion 23, which is internally threaded to receive the lamp 24, and also provides a means whereby the reflector is detachably mounted with relation to the remaining structure. The insulating member is recessed to provide a housing for the contact spring 25, which is provided to engage the center contact of the lamp 24, the contact spring being connected with one of the arms, such as 16, the other arm as 15, being in electrical connection with the plate 21. The opposite ends of said arms, which are secured to the

element 13, are also provided with means whereby an electrical connection may be made therewith to supply current through said arms to the lamp socket and contact spring 25 of the lamp socket and reflector support 19. To this end, the arms are each provided with a conductor, respectively designated 26 and 27, which respectively contact with conductors 28 and 29, arranged within the insulating member 13, the conductors being held by means of the screws 30. One end of each of the conductors 28 and 29, extends beyond the edge of the insulating member to allow a connector 31, having the conductors 32 and 33 extending therefrom to provide and complete a connection between said conductors 28 and 29, and a cell (not shown) which may be stored upon the person of the refractionist.

It is manifest that the arrangement just described provides a means whereby the lamp 24, may be illuminated with the reflector and chart holder arranged in any of its various positions of adjustment.

The reflector 14 is closed by the element 34, which is provided with an aperture 35, having the guideways 36-36, arranged upon opposite sides of the opening. The guideways are provided to receive any one of several different charts 37, and to hold said charts in front of the lamp 24, when arranged to close the opening.

It is, of course, understood that any of the several charts may be interchangeably arranged across the opening, depending upon the test which the refractionist desires to perform, as for instance, should the refractionist desire to subject the patient to a disassociation, dynamic, retinoscopic, or accommodation amplitude test, the various charts employed will be provided with means, whereby these or other tests may be accomplished.

Provision is made whereby the element 34, having the opening 35, is rotatable, this being of advantage in performing certain tests, such as a near point astigmatism test, in which it is advantageous to rotate the chart before the eyes of the patient.

The reflector may be provided with indicia 38, corresponding to all, or part of the meridians of a circle, and the chart holder may be provided with a knob 38', whereby the chart holder may be rotated and said holder may also be provided with a mark, such as 39, which will advise the refractionist as to the degree of angularity, to which the rotatable chart holder has been rotated.

It will be noted that the manner of supporting the reflector and the chart holder, that is, by means of the arms 15 and 16 connected, as illustrated, provides a parallelogram, which insures against rotation of the chart holder upon movement thereof to and from one eye or the other of the refraction-

ist, which, thus, at all times maintains the axes of said charts in proper horizontal and vertical relation, regardless of the position which said chart holder is caused to assume upon movement thereof from one eye to another, or to and from an intermediate position.

The device is also capable of use in conjunction with a rod of a photoptometer, such as shown in Fig. 3, it being evident that this may be accomplished by providing a support or standard 40, which is movably arranged upon the bar 41, the standard having the part 42 provided for the separable attachment of the chart holder and its associated elements.

From the foregoing explanation of the construction and operation of the device, it is manifest that a means is provided, whereby any desirable chart may be interchangeably mounted and illuminated, and that said device may be shifted from one position to another, without varying the position of the axes of the chart or chart holder.

It is also manifest that a construction is provided, whereby the chart and chart holder may be rotated relatively to a support therefor into coincidence with any meridian.

In addition, it is manifest that the structure is also capable of association and co-operation with a bar of a photoptometer.

Having described the invention what I claim and desire to cover by Letters Patent is:

1. In a device of the class described, the combination of a mounting element, a chart holder and lamp support and a connection between said mounting element and said support, the elements of said connection permitting lateral movement of said support and including means for fixedly holding said support in one of several positions of adjustment and describing a parallelogram whereby the support is movable and the alignment of a chart holder carried thereby is maintained during movement relatively to said mounting element.

2. In a device of the class described, the combination of a mounting element, a chart holder and lamp support, for illuminating the chart holder, a pair of links pivotally connected with said mounting element and chart holder and lamp support, and means for fixedly supporting said chart holder in various positions of adjustment relatively to the mounting element.

3. In a device of the class described, the combination of a mounting element, a chart holder, and means carried by the chart holder for illuminating the chart holder, a pair of pivoted links connecting said mounting element and chart holder together, and means for holding said chart holder in various positions of adjustment relatively to the mounting element, said links providing conductors

for the illuminating means carried by the chart holder.

4. In a device of the class described, the combination of a mounting element, a reflector providing a chart holder, means for securing a lamp provided in said reflector, conducting elements providing a connection between said mounting element and means, said conducting element providing means whereby said reflector is movably secured to the mounting element and means for holding said reflector in various positions of adjustment relatively thereto.

5. In a device of the class described, the combination of a mounting element, a chart holder suspended from said mounting element, said chart holder being movable from one side of the center of said mounting element to the other, means for fixedly supporting said chart holder in either of said positions, and means for maintaining the horizontal alignment of the axis of said chart holder when said chart holder is arranged upon one side or the other of said center.

6. In a device of the class described, the combination of a mounting element, a chart holder secured for movement to said mounting element, said chart holder being movable from one side of the center of said mounting element to the other, and said chart holder including means whereby a chart may be rotated relatively to the chart holder.

7. In a device of the class described, the combination of a mounting element, a chart holder, and means for connecting said chart holder and mounting element together, said means providing means whereby said chart holder may be moved laterally in opposite directions, and providing means for holding said holder against rotation during said movement.

8. In a device of the class described, the combination of a mounting element, a chart holder, said chart holder being movable laterally in opposite directions, means for holding said holder against rotation upon said movement, and said chart holder including an element mounted for rotation.

In witness whereof, I hereunto subscribe my name this 20th day of January, A. D. 1928.

JACOB COPELAND.
